UNITED STATES PATENT OFFICE.

JOHN SMITH, OF BINGHAM, UTAH.

ADJUSTABLE CUSHION.

1,007,985.

Specification of Letters Patent.

Patented Nov. 7, 1911.

Application filed August 27, 1910. Serial No. 579,318.

To all whom it may concern:

Be it known that I, JOHN SMITH, a citizen of the United States of America, residing at Bingham, in the county of Salt Lake 5 and State of Utah, have invented certain new and useful Improvements in Adjustable Cushions, of which the following is a specification, reference being had therein to the accompanying drawing.

10 This invention relates to cushions for chairs, settees, and the like, and the principal object of the same is to provide novel cushions for the head and the back which are adjustably connected to the chair so that 15 they can be readily arranged in positions desired by the occupant of the chair.

In carrying out the objects of the invention generally stated above it will be understood, of course, that the essential features 20 thereof are necessarily susceptible of changes in details and structural arrangements, one preferred and practical embodiment of which is shown in the accompanying drawings, wherein:—

25 Figure 1 is a perspective view of a rocking chair equipped with the improved cushions. Fig. 2 is a central vertical sectional view taken on the line 2—2, Fig. 1. Fig. 3 is a detail perspective view of the head 30 cushion. Fig. 4 is a similar view of the back cushion. Fig. 5 is a detail perspective view of one set of the supporting rollers. Fig. 6 is a central vertical sectional view thereof. Fig. 7 is a detail perspective view of one 35 of the rollers.

Referring to the accompanying drawings by numerals, it will be seen that the improved adjustable cushions have been shown in connection with the back of a rocking 40 chair 1, the upper horizontal bar 2 of said back having its lower edge provided with a pair of spaced hanger staples 3, said staples having their body centrally divided by a vertical pin 4 to provide independent bearing 45 spaces for the two rollers 5 and 6.

The upper edge of the lower horizontal bar 7 is provided with a pair of spaced staples 8 each of which is centrally divided into two independent bearing spaces by the 50 pins 10 for the reception of the rollers 11 and 12. Rollers 5 and 11 of the upper and lower staples 3 and 8 are connected by the endless straps 13, and rollers 6 and 12 are connected by the endless straps 14.

55 Straps 13 carry the horizontally arranged head cushion 15 which has its upper rear

corner hinged thereto so that the same can be raised or lowered relative to said straps. Straps 14 have the upper rear corner of the lower section 16 of the back rest hinged 60 thereto for a similar purpose. Said back rest is composed of the two sections 16 and 17 which have a hinge connection so that one section can be rocked onto the other section to increase the thickness of the cushion, or spread apart, as shown in the drawing to provide a wide rest for the back. 65

It will be understood from the foregoing that the improved cushions can be readily adjusted for the comfort of the user, irrespective of size, and also that the sectional back rest or cushion provides means whereby a wide rest or a thick narrow rest can be readily provided. 70

As is clearly shown in Fig. 1 of the accompanying drawings, the head and back rests project across and are slideable on the vertical side bars of the back of the chair and are held in contact with said bars by the adjusting straps. This arrangement 75 causes the rests to be supported by said bars when in use so that the pressure thereon will not exert a strain on the adjusting straps. 80

What I claim as my invention is:—

1. In combination with a chair provided 85 with a back rest, said rest including upper and lower horizontal bars, spaced roller supports carried by the lower edge of said upper bar, spaced roller supports carried by the upper edge of the lower bar, rollers 90 carried by the upper and lower supports, adjusting bands connecting the upper and lower rollers, a head cushion carried by one set of bands, and a back cushion carried by the other set of bands. 95

2. In combination with a chair provided with a back rest, said rest including upper and lower bars, rollers carried by said bars and arranged in pairs, adjusting bands connecting the upper and lower rollers, a head 100 cushion carried by one set of bands, and a back rest formed of two sections flexibly connected, one of said sections being connected to one set of said bands.

3. In combination with a chair provided 105 with a back rest, upper and lower supports carried thereby and arranged in independent sets, supporting bands arranged in independent sets and engaging the sets of supports, a head cushion carried by one set of 110 bands, and a back cushion carried by the other set of bands.

4. In combination with a chair provided with a back rest, said rest including upper and lower horizontal bars and connecting side bars, a plurality of sets of endless adjusting bands carried by said horizontal bars, a head cushion carried by one set of bands and having its ends overlapping and slid able on the side bars, and a back cushion carried by another set of the bands and hav-

ing its ends overlapping and slid able on 10 said side bars.

In testimony whereof I hereunto affix my signature in presence of two witnesses.

JOHN SMITH.
